US0D1053384S

(12) **United States Design Patent** (10) **Patent No.:** **US D1,053,384 S**
(45) **Date of Patent:** **** Dec. 3, 2024**

(54) **COVER**

(71) Applicant: **National Diversified Sales, Inc.**,
Woodland Hills, CA (US)

(72) Inventors: **David Rusch**, Springville, CA (US);
Roberto Orozco, Merced, CA (US)

(**) Term: **15 Years**

(21) Appl. No.: **29/808,607**

(22) Filed: **Sep. 21, 2021**

(51) LOC (14) Cl. **25-02**

(52) U.S. Cl.
USPC **D25/36**

(58) **Field of Classification Search**

USPC D25/35, 36
CPC . H02B 1/50; H02G 3/081; H02G 3/14; H02G
9/10; E02D 29/14

(57) **CLAIM**

The ornamental design for a cover as shown and described.

DESCRIPTION

FIG. 1 is a perspective view from above of a cover, showing our new design;

FIG. 2 is a perspective view thereof from below;

FIG. 3 is a top view thereof;

FIG. 4 is a front view thereof;

FIG. 5 is a bottom view thereof;

FIG. 6 is a left side view thereof;

FIG. 7 is a right side view thereof; and,

FIG. 8 is a back view thereof.

Those portions of the figures shown in dotted lines form no part of our invention, but are included to show the context and environment of the invention.

1 Claim, 4 Drawing Sheets
